UNITED STATES PATENT OFFICE.

LE ROY WILLOUR, OF ASHLAND, OHIO.

JACK.

1,201,413.

Specification of Letters Patent. Patented Oct. 17, 1916.

Application filed September 27, 1915. Serial No. 52,921.

To all whom it may concern:

Be it known that I, LE ROY WILLOUR, a citizen of the United States, residing at Ashland, in the county of Ashland and State of Ohio, have invented certain new and useful Improvements in Jacks, of which the following is a specification.

My invention relates to improvements in lifting jacks, of the type which embody generally a lift-bar having teeth, and a plurality of pawls engaging the teeth for raising and lowering the lift-bar.

An important object of the invention is to provide means to reverse the operation of the pawls, which are simple in construction, inexpensive to manufacture, and compact.

A further object of the invention is to provide novel and simple adjustable means, carried by the lift-bar, to contact with the load.

A further object of the invention is to provide a lifting jack of the above mentioned character, which is reliable and expeditious in operation.

Other objects and advantages of the invention will be apparent during the course of the following description.

In the accompanying drawings forming a part of this specification and in which like numerals are employed to designate like parts throughout the same, Figure 1 is a side elevation of a lifting jack embodying the invention, Fig. 2 is a central vertical longitudinal sectional view through the same,

35 parts in elevation, with the pawl reversing rod or bar held in the inactive position, Fig. 3 is a similar view, with the pawl reversing rod or bar in the active position, and the operating handle in the lowered position, Fig. 4 is a similar view with the operating handle in the elevated position, Fig.

5 is a perspective view of the pawls, Fig. 6 is an enlarged horizontal sectional view taken on line 6-6 of Fig. 1, Fig. 7 is a

45 transverse sectional view taken on line 7-7 of Fig. 6, Fig. 8 is an end elevation of a slightly different form of means for holding the pawl reversing rod or bar in the outer or inactive position, with the rod or bar in the active position, Fig. 9 is a similar view with the rod or bar in the inactive position, and, Fig. 10 is a longitudinal sectional view taken on line 10-10 of Fig. 8.

In the drawings, wherein for the purpose 55 of illustration is shown a preferred embodiment

ment of my invention, the numeral 15 designates a hollow standard, shown square in cross-section, while the same may be constructed in any other suitable shape. This standard is provided at its lower end with a foot or base 16, as shown. Formed upon one side of the hollow standard 15 and near its top is a laterally extending housing 17, for a purpose to be described. Mounted to slide within the hollow standard 15 is a lift-bar 18, having ratchet teeth 18'. This lift-bar is preferably hollow and preferably formed square in cross-section, as shown. This lift-bar has a longitudinal opening 19, preferably square in cross-section. The opening 19 leads into a reduced circular opening 20 at the upper end of the lift-bar.

Mounted to move longitudinally within the opening 19 of the lift-bar 18, but having no screw-threaded engagement therewith, is a screw 21, the lower end of which is provided with a transverse pin 22, operating in the corners of the opening 19, thus preventing rotation of the screw 21. The screw 21 extends outwardly beyond the head 23 of the lift-bar and has a head 24, attached thereto by any suitable means. Arranged between the heads 24 and 23 is an adjusting nut 25, having screw-threaded engagement with the screw 21. By rotating this adjusting nut with respect to the lift-bar, the screw 21 is moved upwardly with relation thereto, whereby the jack may be conveniently used in raising loads of different heights. While I prefer to equip the lift-bar 18 with the adjustable screw 21, it is to be understood that the invention is in no sense restricted to this screw, as satisfactory results may be obtained without its employment.

The numeral 26 designates an operating lever, having an outer tubular portion 27 for receiving the inner end of a handle (not shown). The lever 26 has its inner end forked, providing spaced lines or sides 28, which are apertured at 29, for receiving a transverse pin 30, extending through openings 31, formed in the sides of the housing 17, as shown.

Arranged within the forked end of the lever 26, between the tines 28, are operating pawls 32 and 33, pivotally connected therewith by means of pins 34 or the like. The outer pawl 32 is longer than the inner pawl, as shown. The pawls 32 and 33 are pro-

vided adjacent their pivots with openings 35, receiving the ends of a spring 36, engaging these pawls and coiled about the pins 34. The function of this spring is to hold the pawls in proper contact with the teeth 18'. The pawls 32 and 33 are provided adjacent their pivots with depending extensions or fingers 37 and 38 respectively, preferably of the shape shown, and which are preferably formed integral with the pawls. While I prefer to mount both pawls upon the operating lever, yet it is to be understood that the invention is not necessarily restricted to such arrangement, as satisfactory results are obtainable by pivoting one pawl upon the standard or housing and the other upon the operating lever.

The numeral 39 designates a preferably horizontal reciprocatory preferably cylindrical pawl reversing rod or bar, provided at its inner end with upstanding fingers 40 and 41, preferably formed integral therewith and adapted to contact respectively with the depending fingers 37 and 38, for a purpose to be described. The reversing rod or bar 39 is mounted to slide or reciprocate in a sleeve 43, cast upon the lower end of the housing 17. A suitably stiff coil spring 45 surrounds the inner end of this rod or bar and serves to move it inwardly, but will permit of its reciprocatory movement. One side of the rod or bar 39 is provided with an elongated groove or recess 46, adjacent the inner end of which is disposed a notch 47. The sleeve 43 is provided with a transverse recess 48, receiving a preferably reciprocatory latch 49, adapted to enter the recess 46 and notch 47, and forced inwardly by a spring 50. A rod 51 is rigidly attached to the latch 49 and operates through an opening 52 and is provided at its outer end with a head 53 for convenient operation. The rod or bar 39 is provided at its outer end with a head or knob 39 whereby it may be conveniently moved longitudinally.

From the foregoing description it is obvious that when the latch 49 enters the notch 47, as indicated in Fig. 6, the reversing rod or bar 39 will be held in the outer or inactive position. When the rod or bar 51 is moved outwardly, the latch 49 is removed from the notch 47 and the spring 55 shifts the rod or bar 39 inwardly, the rod 51 being released so that the latch 49 may enter the longitudinal opening or groove 46. The latch 49, while remaining in this groove, does not prevent the reciprocatory movement of the rod or bar 39, within certain limits. The rod or bar 39 cannot turn upon its longitudinal axis, as it carries a transverse pin 52, operating in longitudinal grooves 53, formed upon the inner side of the sleeve 43.

In Figs. 8 to 10 inclusive, I have shown a different form of means for detachably holding the pawl reversing rod or bar 39 in

the outer position. In this construction, the latch 49 is dispensed with, together with the groove 46 and notch 47, while all of the parts of the device remain identical. The rod or bar 39 is moved outwardly, and when 70 the pin 52 passes out of the grooves 53, such rod or bar is turned upon its longitudinal axis, whereby the ends of the pin 52 engage the end wall of the casing 43, thus holding the rod or bar 39 in the outer position, and 75 the fingers 40 and 41 in a position whereby they cannot contact with the fingers 37 and 38 respectively.

The operation of the lifting jack is as follows: To raise the lift-bar 18 the pawl reversing rod or bar 39 is held in the outer or inactive position, whereby its fingers 40 and 41 do not contact with the fingers 37 and 38 respectively. Upon the down stroke of the lever 26, the inner pawl 33 will advance 80 the lift-bar upwardly a step and upon the end of the down stroke the outer pawl 32 will trip upon its tooth and engage beneath the next tooth above the tooth engaged by the pawl 33. Upon the up-stroke of the 90 lever 26, the outer pawl 32 raises the lift-bar 18 a step and the inner pawl 33 trips upon its tooth to engage beneath the next lower tooth. In this manner the lift-bar is advanced upwardly a step when the lever 95 26 is swung in either direction. To lower the lift-bar 18 the reversing rod or bar 39 is released and moves inwardly, so that its fingers 40 and 41 are adapted to contact respectively with the fingers 37 and 38, as 100 more clearly illustrated in Figs. 3 and 4. At this point it might be well to state that the spring 45 is stiffer than the spring or springs 36 and can overcome the same. When the lever 26 is swung downwardly, in 105 the lowering operation of the lift-bar 18, as soon as the inner pawl 33 is elevated sufficiently to take the load of the lift-bar from the outer pawl 32, the outer pawl swings outwardly, disengaging its tooth 18', as the 110 finger 37 thereof is contacting with the finger 40. Upon the up-stroke of the lever 26, the finger 40 remaining in contact with the finger 37, the pawl 32 is held in the outer 115 position so that it will not engage with the next upper tooth 18, but skips it and engages with the second upper tooth, thus effecting a lowering movement of the lift-bar, during the greater portion of the up-stroke of the 120 operating lever, as said lift-bar descends with the pawl 33. When the lever reaches the end of its up-stroke, the outer pawl 32 slightly elevates the lift-bar, relieving the load from the inner pawl, whereby this inner pawl swings outwardly, as its finger 125 38 contacts with the finger 41. Upon the down stroke of the lever the inner pawl does not contact with the adjacent tooth 18', but skips it and engages the next upper tooth, thus effecting a lowering movement of the 130

lift-bar, for the greater portion of the down stroke of the operating lever, as the lift-bar descends with the outer pawl.

It is to be understood that the form of my 5 invention herewith shown and described is to be taken as a preferred example of the same, and that various changes in the shape, size, and arrangement of parts may be resorted to without departing from the spirit 10 of the invention or the scope of the subjoined claims.

Having thus described the invention, I claim:

1. In a lifting jack; a standard; a lift-bar 15 having slidable engagement therewith and provided with teeth; an operating lever pivotally connected with the standard; a plurality of pawls pivotally mounted upon the operating lever to engage the teeth of the lift-bar, said pawls being provided with depending fingers to move them; spring means 20 to move the pawls into engagement with the teeth of the lift-bar; a reciprocatory shifting member arranged near the lower ends of the pawls and having upstanding fingers to 25 contact with the fingers of the pawls; a spring to move the reciprocatory shifting member in one direction; and means to hold the shifting member in the outer inactive 30 position.
2. In a lifting jack; a standard; a lift-bar having slidable engagement therewith and provided with teeth; an operating lever pivotally connected with the standard; a 35 plurality of pawls having their lower ends pivotally connected with the operating lever and their upper ends adapted to contact with the teeth of the lift-bar, said pawls being provided adjacent their lower pivoted ends 40 with depending fingers; spring means to move the pawls into engagement with the teeth of the lift-bar; a reciprocatory shifting member arranged near and beneath the lower ends of the pawls and having upstanding
3. In a lifting jack; a standard; a lift-bar having slidable engagement therewith and provided with teeth; an operating lever 50 pivotally connected with the standard; a plurality of pawls pivotally mounted upon the operating lever to engage the teeth of the lift-bar, said pawls being provided with depending fingers to move them; spring 55 means to move the pawls into engagement with the teeth of the lift-bar; a reciprocatory shifting rod arranged near the fingers of the pawls and having fingers to contact therewith, said rod being provided with a recess; a spring to move the rod inwardly; and a spring pressed latch adapted to enter the recess in the rod to hold it in the outer position.
4. In a lifting jack; a standard; a lift-bar 65 having slidable engagement with the standard and provided with teeth; a laterally extending housing secured to the standard and provided with a sleeve having a longitudinal groove; an operating lever pivotally 70 mounted within the housing; a plurality of pawls pivotally mounted upon the operating lever to engage the teeth of the lift-bar, said pawls being provided with fingers to move them; spring means to move the pawls 75 into engagement with the teeth of the lift-bar; a reciprocatory shifting bar mounted to slide within the sleeve and having a transverse pin operating in the groove, said bar being provided with fingers to contact with the first named fingers; and means to move the bar inwardly.

In testimony whereof I affix my signature in presence of two witnesses.

LE ROY WILLOUR.
